F. S. RECE

SIDE PANEL FOR CRIBS

Filed April 7, 1924

UNITED STATES PATENT OFFICE.

FRANK S. REECE, OF DALLAS, TEXAS.

SIDE PANEL FOR CRIBS.

Application filed April 7, 1924. Serial No. 704,816.

This invention relates to new and useful improvements in side panels for cribs.

This invention has particularly to do with the type of children's cribs which are 5 mounted on wheels and adapted to be moved into position along the side of the mother's bed or wheeled onto a porch or lawn or other places. Such cribs have screened sides and a cover or side and end panels 10 which extend some distance above the mattress to prevent the infant or young child from falling or climbing from the crib. When the crib is used along side of a bed, it is necessary to lower the adjacent side 15 panel and my invention has to do with such a panel.

The object of the invention is to provide a side panel which may be quickly and easily manipulated so as to be raised or 20 lowered and slid under the mattress support without unnecessary effort, and which will always be in a convenient position to operate.

A particular object of the invention is 25 to provide means in connection with the side panel for limiting the outward movement of the same and also for forming a hinge when the panel is swung upwardly or downwardly.

30 A further object is to provide a pair of hinged trailing hooks on the lower edge of the panel co-acting with supporting rails and keepers to limit the outward sliding movement of the panel and to hinge it to the bottom of the crib for swinging.

A construction designed to carry out the invention will be hereinafter described together with other features of the invention.

40 The invention will be more readily understood from a reading of the following specification and by reference to the accompanying drawings, in which an example of the invention is shown, and wherein:

45 Fig. 1 is a plan view of a crib equipped with a side panel made in accordance with my invention and slid under the mattress support,

50 Fig. 2 is a cross-sectional view on the line 2—2 of Fig. 1,

Fig. 3 is a similar view the side panel being raised,

55 Fig. 4 is a detail of the panel and the supporting rail at one side, the hook being at the entrance to the inclined sump,

Fig. 5 is a similar view showing the hook

in engagement with the keeper and the panel raised, and

Fig. 6 is a similar view showing the panel at the outer end of its sliding movement just prior to raising.

In the drawings the numeral 10 designates the bottom frame of a crib with end panels 11 and a hinged side panel 12, sometimes called a back panel. In the frame is 65 fixed a mattress support 13. The frame is supported on wheels 14. These parts are typical and have no part in the invention.

My improved side panel 15 entirely closes one side of the crib and is sometimes referred to as the front panel. The end panels 11 may have angular strips 16 or other stops, on their inner sides to be engaged by the panel 15, whereby the latter is supported in an upright position in which 75 it may be suitably fastened by means not shown.

Within the frame 10 under the mattress support 13, I mount a pair of transverse rails 17 intersecting with a flat side bar 80 18. The rails may be secured to the ends of the frame. The side panel 15 slides on the rails 17 between said rails and the support 13. On the inner side of the top member of the panel are a pair of spaced finger 85 recesses 19, whereby the panel may be grasped and manipulated.

On the inner side of the lower edge portion of panel and adjacent each end I provide a recess 20 in which a hinge plate 21 90 is fastened. At its inner or upper end the plate has ears 22 receiving a pintle 23 on which the eye 24 of a hook 25 is mounted. The hook is thus hinged in the recess. This hook has a reduced and elongated shank 95 26 and is preferably made of a flat piece of metal bent upon itself to form the eye and further bent to form a down-turned bill 27.

When the panel is slid on the rails 17 the bills of the hooks ride on said rails as is 100 indicated in Fig. 4. When the panel is pulled outward the bills slide down inclined sumps 28 in the forward ends of the rails and come into engagement with the lips of angular keepers 29, whereby the 105 sliding and outward movement of the panel is arrested. The hooks become hinge links and the eyes 24 provide hinge connections with the plates 21, whereby the panel may be swung upwardly to the position shown 110 in Fig. 3.

The trailing of the hooks over the rails

so that they readily ride down the sumps 28 and engage the keepers 29, is an important feature which makes for convenience, simplicity and ease and rapidity of operation. Equally so, when the panel is lowered and slid under the support 13, the hooks owing to the under-bent bills 27, ride up the inclined sumps 29 and over the rails. The hooks may limit the inward sliding of 10 the panel by engaging the rear side of the frame or suitable stops (not shown) may be used.

When it is desired to raise the side panel 15 it is merely necessary to place the fingers 15 in the recesses 19 and pull the panel outwardly until the top member can be grasped. The panel being of light weight and sliding freely is easily handled. The panel is pulled outwardly until the hooks 25 having ridden 20 down the inclined sumps 28, engage the keepers 29; whereupon the said hooks function as hinges permitting the panel to be swung up to the position shown in Fig. 3.

When it is desired to lower the side panel 25 15 it is first swung outwardly and as it is swung downwardly its lower edge is pushed inwardly, which starts the hooks up the inclined sumps. It will be noted that there is sufficient space between the panel and the 30 mattress support to allow this movement. When the panel has been lowered to a horizontal position the sliding movement may be completed, the hooks riding out of the sumps and onto the rails 17.

35 The success of the device resides in the freedom and lack of effort with which it may be operated as well as its simple and economical construction. By completely housing the side panel under the mattress 40 support, it is out of the way so that the crib may be moved close to the bed and without interference from the side panel. Sometimes these side panels are merely lowered and the baby must be lifted over the same 45 or they are not properly housed.

Various changes in the size and shape of the different parts, as well as modifications and alterations may be made within the scope of the appended claims.

50 What I claim, is:

1. A hook for a slide-under panel for a crib comprising an eye pivotally mounted upon the panel, and an outwardly bent bill 55 slidably mounted upon a support and disposed to interlock with a keeper and pivot thereon.

2. In a crib, the combination with a support having a keeper, of a side panel, and a hook hinged to the lower edge of the panel 60 for sliding on the support away from the

keeper when the panel is slid into the crib and for interlocking with and hinging on the keeper when the panel is swung upwardly.

3. In a crib, the combination with a support having a keeper, and an inclined sump 65 leading to the keeper, of a slidable and foldable side panel, and a hook hinged to the lower edge of the panel in a position to slide down said inclined sump and engage said keeper to hinge the side panel. 70

4. In a crib, the combination with a frame and a mattress support in the frame, of guide rails under the support, a side panel 75 slidable on said rails under said mattress support, hooks hinged to the lower edge of the panel, and keepers on the frame interlocking with said hooks to form a pivot for swinging the panel upward.

5. In a crib, the combination with a frame and a mattress support in the frame, of 80 guide rails in the frame provided with inclined sumps, keepers at the upper outer ends of the sumps, a foldable and slidable side panel, and hooks hinged to the panel and having outwardly open bills trailing on the 85 rails and in the sumps thereof to interlock with the keepers to hinge the side panel.

6. In a crib, the combination with a frame and mattress support in the frame, of guide 90 rails in the frame provided with inclined sumps, inwardly extending keepers at the upward outer ends of the sumps, a foldable and slidable side panel, plates fastened to the panel, and hooks hinged to the plates 95 and having under-turned bills sliding on the rails and interlocking with the keepers to hinge the side panel.

7. In a crib, the combination with a frame and mattress support in the frame, of guide 100 rails in the frame provided with inclined sumps, inwardly extending keepers at the upper outer ends of the sumps, a foldable and slidable side panel, plates fastened to the panel, and hooks hinged to the plates 105 and having under-turned bills sliding on the rails and interlocking with the keepers, said hooks being projected beyond the frame to engage the frame and limiting the inward sliding movement of the side panel.

8. In a crib, the combination with a support member, of a side panel member horizontally slidable thereon, a keeper upon one of said members, and a hook pivoted upon the other member to face said keeper and normally separated therefrom and disposed to interlock and hinge upon the keeper when the panel is slid outwardly. 110

In testimony whereof I affix my signature.
